UNITED STATES PATENT OFFICE.

VÁCLAV OTAKAR DEYL, OF VINOŘ, NEAR PRAGUE, AUSTRIA-HUNGARY.

TOPPING-MACHINE.

1,096,695.

Specification of Letters Patent.

Patented May 12, 1914.

Application filed November 14, 1913. Serial No. 801,046.

To all whom it may concern:

Be it known that I, VÁCLAV OTAKAR DEYL, a subject of the Emperor of Austria-Hungary, residing at Vinor, near Prague, Bohemia, Austria-Hungary, have invented certain new and useful Improvements in Topping-Machines, of which the following is a specification.

This invention relates to an improvement in topping machines for turnips, beet roots and the like having a topping knife which is vertically adjustable in its longitudinal direction to suit the different heights of the roots, the movement of the knife being produced by means of a wheel. In machines of this kind the wheels are adjustable only in the vertical direction for determining the vertical position of the knives. In rows of roots, however, all the roots are not in a straight line, but a little way away from the center line, frequently to such an extent that the wheel determining the vertical position of the knives, passes the root, and in that way an excessive section of the root is cut. As the whole machine cannot be guided by the front steering device sufficiently quickly to enable the wheel, which is situated in the center of the machine, to strike each root, it has been found essential to arrange the wheel inside the machine so that it can be moved to the side instantaneously. According to this invention this is done by the wheel spindle with its roller guides being adjustably mounted by means of a carriage on a cross-bar of the machine frame so that it can be pulled by means of a connecting rod and hand lever instantaneously to the side, to the right or to the left from the central line and exactly above the root. This hand lever can then be coupled by means of a connecting rod to the steering lever for the front wheels, so that the person guiding the wheel, simultaneously effects the steering of the front wheels.

A construction according to this invention is illustrated by way of example in the accompanying drawing, in Figure 1 in back view and in Fig. 2 in plan.

On the machine frame or on its cross bar 1 is mounted in roller guides 2 and so as to be vertically adjustable a spindle 3 the lower end of which forms a bearing 4 for the topping knife 5. The knife is reciprocated in its longitudinal direction by the driving wheel 10 by means of a series of pivoted rods 6, 7, 8, 9. On the cross-bar 1 is also loosely

mounted a carriage 11 connected by means of a rod 12 to a double armed hand lever 13 which can be moved by the driver when he is sitting on the machine, from where he can see the turnips. To the carriage 11 are secured roller guides 14 in which the spindle 15 with the wheel 16 determining the vertical position of the knives, is vertically adjustably mounted. This wheel spindle 15 is connected by means of bolts 16 and 17 to the spindle 3, not rigidly, however, the wheel spindle 15 being provided with two sleeves 18 and 19 loosely mounted on the bolts 16 and 17. These bolts are adjustably mounted in the slots 20 and 21 of the knife spindle whereby the thickness of cut can be regulated. The bottom bolt 17 is controlled by a double-armed lever 22, on one or the other arm of which can be mounted a weight 23 for loading or relieving the wheel.

It will be seen that when a root stands too far away from the central line of the row (Fig. 1) so that it would not be touched by the wheel, the carriage 11 and the wheel spindle 15 can be adjusted so that the wheel 16 would be exactly above the root, by suitably adjusting the hand lever 13 in the direction of the arrow I, so that the wheel strikes correctly the head of the root, and the topping knife correctly cuts it.

As the driver of the wheel 16 and the driver of the front wheels 24 would usually not agree, and in order further to economize one attendant, the steering lever 25 of the front wheels is connected by a rod 26 to the hand lever 13, so that the driver of the wheel 16 can simultaneously steer it and the front wheels, which is of considerable importance when the rows of roots are not straight. The amount of steering of the front wheels is regulated by means of holes 27 provided in the lateral steering lever 25. When the connecting rod 26 is not in use, the front end of the same is placed into a fork 28.

The topping knife 5 must cut the root at the moment that the wheel is still on it. As the topping knife is in oblique position, it would happen in the event of a root being at the side, that the wheel would roll off the root before the topping knife becomes operative, and the root would be cut too deep. This disadvantage is remedied by staggering the single disks of the wheel 16, in accordance with the oblique position of the edge of the knife 5 and in the longitudi-

nal direction of the machine. Fig. 2 shows the arrangement of the said disks. Owing to this arrangement, the single disks pass the root consecutively, and keep the topping 5 knife raised so long as a disk rolls over the root. The consequence is that all the roots are cut to the same thickness that is, even roots which are planted far away at the side of the row.

10. What I claim as my invention and desire to secure by Letters Patent is:—

1. In a topping machine comprising a frame, a wheel, and a topping knife which is vertically adjustable to the height of the 15 wheel, the combination of a carriage and a hand lever moving the same, said wheel being connected to the carriage so that it can be moved to the side.

2. In a topping machine comprising a frame, a wheel, and a topping knife which is vertically adjustable to the height of the wheel, the combination of a carriage, a spindle to which said wheel is attached, and a hand lever adapted to move the wheel 25 to one side.

3. In a topping machine comprising a frame, a wheel, and a topping knife which is vertically adjustable to the height of the wheel, the combination of a hand lever, a 30 connecting rod therefor, a carriage attached to one end of the connecting rod, a wheel spindle, roller guides therefor, sleeves on

the wheel spindle, bolts passing therethrough and a spindle for the knife to which said bolts are connected.

35

4. In a topping machine comprising a frame, a topping knife, front wheels, steering gear for said front wheels and a wheel for adjusting the height of the topping knife, the combination of a hand lever, a 40 connecting rod therefor, a carriage attached to one end of the connecting rod, a wheel spindle, roller guides therefor, sleeves on the wheel spindle, bolts passing therethrough, a spindle for the knife to which 45 said bolts are connected, and an adjustable rod connecting the steering gear to the hand lever, for the purpose set forth.

5. In a topping machine comprising a frame, a wheel and an oblique topping knife 50 which is vertically adjustable to the height of the wheel, the combination of single disks making up the wheel and staggered to suit the oblique knife, a carriage and a hand lever moving the same, said wheel being 55 connected to the carriage so that it can be moved to the side.

In testimony whereof I have signed my name to this specification in the presence of two subscribing witnesses.

VÁCLAV OTAKAR DEYL.
